(57) **CLAIM**

The ornamental design for a load bearing attachment arm, as shown and described.

DESCRIPTION

FIG. 1 is an environmental view of the present design; FIG. 2 is a perspective view of the present design; FIG. 3 is a bottom view of the present design; FIG. 4 is a right side view of the present design, a corresponding left side view being a mirror image thereof; FIG. 5 is a top view of the present design; FIG. 6 is a rear view of the present design; and, FIG. 7 is a front view of the present design.

The broken lines shown in the drawings are included for the purpose of illustrating environmental structure and form no part of the claimed design.
